CLAIM

The ornamental design for a satellite speaker, substantially as shown and described.

DESCRIPTION

FIG. 1 is a perspective view of a first embodiment of a satellite speaker as seen from the front, top and side;

FIG. 2 is a top view thereof;

FIG. 3 is a front view thereof;

FIG. 4 is a bottom view thereof;

FIG. 5 is a back view thereof;

FIG. 6 is an opposite side view thereof; and,

FIG. 7 is a side view thereof.

The dotted line portions of the drawings represent environmental structure only and form no part of the claimed design.
